CONRAD C. SCHOENECK, OF SYRACUSE, NEW YORK.

CASING FOR INCANDESCENT-ELECTRIC-LAMP SOCKETS.

1,025,928.

Specification of Letters Patent.

Patented May 7, 1912.

Application filed January 11, 1911. Serial No. 602,092.

To all whom it may concern:

Be it known that I, CONRAD C. SCHOENECK, of Syracuse, in the county of Onondaga and State of New York, have invented 5 a new and useful Casing for Incandescent-Electric-Lamp Sockets, of which the following is a specification.

This invention has for its object the production of a simply-constructed and economically-manufactured casing for incandescent electric lamp sockets; and it consists in the combinations and constructions hereinafter set forth and claimed.

In describing this invention reference is 15 had to the accompanying drawing in which like characters designate corresponding parts in all the views.

Figure 1 is an unassembled view of this 20 casing for incandescent electric lamp sockets, the cap member and contiguous parts being shown in section. Fig. 2 is a transverse sectional view of said casing, the members thereof being assembled. Fig. 3 is an inner face view of the cap member. Fig. 4 25 is a plan view of the shell member. Fig. 5 is a fragmentary view of the shell and cap member when interlocked. Fig. 6 is a view similar to Fig. 5 illustrating the members 30 prior to being interlocked. Figs. 7 and 8 are fragmentary views of modified forms of my casing.

This casing for incandescent electric lamp 35 sockets, comprises a shell member 1 and a cap member 2 having interlocking means which are brought into and out of interlocking engagement by successive axial and partial rotary movements of the members. The interlocking means comprises internal shoulders 3 formed on one of the members 40 here shown as the cap member 2, the shoulders 3 being located in arcs of less radii than the normal radius of the cap, or of less radii than the radii of the portions of the cap intervening between the shoulders 3; 45 and such interlocking means further includes peripheral shoulders on the other of such members, as the shell member 1, the shoulders 4 being located in arcs of greater radii than the radii of the inner edges of 50 the shoulders 3, or of greater radii than the portions of the shell member intervening between said shoulders 4.

As here shown the shoulders 3 are formed by pressing inwardly portions of the margin 55 of the cap member 2, these portions being spaced at intervals substantially equi-

distant apart, said portions being formed with bearing faces below the shoulders and engaging the outer face of the shell member 1; and the shoulders 4 are in the form of 60 tongues struck from the margin of the shell member 1, such tongues being of substantially the same width as the distance between any two of the shoulders 3. The shoulders 3 and 4 are held in interlocking 65 engagement by a snap catch device comprising a complementary projection 5 and depression or perforation 6 formed respectively in the cap member and shell member, the projection being here shown as pressed 70 inwardly from one of the shoulders 3, and the depression or perforation being shown as formed in the shell member below one of the shoulders 4 and near the slot 7 in the shell for the key of the socket, or near any 75 other yielding portion of the shell member.

In Fig. 7, is shown a modified form of the shoulders on the shell member, such shoulders 8 being shown as formed by pressing outwardly portions of the margin of the 80 shell member 1 in a manner similar to the formation of the shoulders 3 of the cap member, shown in Fig. 3.

In Fig. 8, I have shown another modified form of my invention in which the interlocking shoulders 9, 10 of the cap and shell members are formed by turning inwardly tongues formed on the margin of the cap member, and turning outwardly tongues formed on the margin of the shell member. 90 The cap member is also formed with an internal abutment 11 near its upper end opposed to the internal shoulders 3 of the cap member, and the upper edge of the shell member shoulders against said abutment 95 when the shoulders 3, 4 are interlocked.

In operation the cap member is secured to the supporting fixture by means of the ordinary screw threaded coupling 12, and the socket wired to the conductors leading in through the coupling, and the shell member which is around the socket is moved axially carrying the shoulders 4 between the shoulders 3 of the cap member until the lower edges of the shoulders 4 clear the upper edges of the shoulders 3 and then the shell member is given a partial rotation about its axis until the snap catch device operates. To detach the shell member from the cap member, the portion of the shell 100 member near the slot 7 is pressed inwardly 105 to uncatch the snap catch device, the shell 110

member is rotated in the reverse direction until the shoulders 3, 4 are unlocked and then the shell member is moved axially.

What I claim is:

- 5 1. In a casing for incandescent electric sockets, a shell member, and a cap member, one of said members being formed with internal shoulders spaced apart circumferentially and located in arcs of less radii than the radii of the portions between said shoulders, and the member formed with the internal shoulders being formed with bearing faces below said shoulders for engaging the other member and such other member being formed with external shoulders arranged in arcs of greater radii than the radii of the inner edges of the first-mentioned shoulders and being adapted to interlock with the first-mentioned shoulders, substantially as and for the purpose described.
- 10 2. In a casing for incandescent electric sockets, a shell member and a cap member, the cap member being formed with internal shoulders spaced apart circumferentially and located in arcs of less radii than the radii of
- 15
- 20
- 25

the portions between said shoulders, and the cap member being formed with bearing faces below said shoulders for engaging the shell member and the shell member being formed with external shoulders arranged in arcs of greater radii than the radii of the inner edges of the first-mentioned shoulders and being adapted to interlock with the first-mentioned shoulders, and the cap member being formed with an internal abutment near its upper end and the shell member shouldering against said abutment when the shoulders of the members are interlocked, substantially as and for the purpose specified.

In testimony whereof, I have hereunto signed my name in the presence of two attesting witnesses, at Syracuse, in the county of Onondaga, in the State of New York, this 27th day of December, 1910.

CONRAD C. SCHOENECK.

Witnesses:

S. DAVIS,
G. B. SMITH.
